UNITED STATES PATENT OFFICE

ARTHUR J. BOYNTON AND PAUL ZIMMERMANN, OF CHICAGO, ILLINOIS, ASSIGNEES TO
H. A. BRASSET & COMPANY, OF CHICAGO, ILLINOIS, A CORPORATION OF ILLINOIS

DISTRIBUTING LARGE BELL FOR BLAST FURNACES

Application filed August 31, 1931. Serial No. 560,301.

This invention relates to improvements in blast furnace apparatus and particularly to the construction and control of the distributing large bell.

5 It is an object of the present invention to provide a distributing large bell in a blast furnace which consists of two parts each of which is of a conical shape and provided with a radial cut-out portion in its marginal edge, whereby, by relative rotation of the parts of the bell, the effective size of a distributing opening may be adjusted.

It is further an object of the present invention to provide means for adjusting the 15 effective size of the distributing opening in the large bell from the exterior of the blast furnace without removal of the bell or hopper from the blast furnace.

An additional object of the present invention consists in the provision of means for controlling the effective size of the distributing opening in the large bell of a blast furnace without interruption of the blast furnace operation, and additionally to provide 25 indicating means at a point removed from the blast furnace serving to visually indicate the relative size of the distributing opening in the large bell valve automatically during the operation of the blast furnace.

30 The invention will be more readily understood from the following description taken in connection with the attached drawings, in which

Figure 1 is an elevation partially in section 35 illustrating the operating means for the blast furnace bells;

Figure 2 is an elevation partially in section taken transverse to Figure 1;

Figure 3 is an enlarged detail section of a 40 portion of the driving mechanism;

Figure 4 is a cross section taken on the plane indicated 4-4 on Figure 3;

Figure 5 is an elevation, partially in section and further illustrating diagrammatically circuit connections for an indicator;

Figure 6 is an enlarged cross section on the plane 6-6 of Figure 5;

Figure 7 is an enlarged section on the plane indicated 7-7 in Figure 5;

Figure 8 is an enlarged section taken on the plane indicated 8-8 in Figure 5;

Figure 9 is a plan view illustrating a pair of bells together constituting the distributing valve;

Figure 10 is a vertical section indicated on the plane indicated 10-10 in Figure 9;

Figure 11 is a plan view similar to Figure 9 illustrating a modified construction of the bells;

Figure 12 is a vertical section indicated on the plane 12-12 in Figure 11, and

Figure 13 is a vertical section indicated on the plane 13-13 in Figure 11.

An important feature of the present invention relates to the improved construction of the distributing valve in a blast furnace. As shown in Figures 9 and 10 we employ an upper conical valve 10 and a lower conical valve 12, each of which has a cut-out portion 14 in its marginal edge extending approximately $\frac{1}{2}$ of the circumference. The bells 10 and 12 are co-axially associated and arranged for relative rotation whereby the effective size of a distributing opening, determined by the relative positions of the semi-circular cut-out portions in the marginal edges of the bells 10 and 12, may be varied as desired, the object being to distribute the stock fed from the hopper 14 with which the bells 10 and 12 are associated towards the central part of the furnace to obtain a more even distribution.

As shown in Figure 10 the lower bell 12 has a circular groove 16 adapted to cooperate with a circular ridge 18 on the inner surface of the upper bell 10 to center the bells with respect to each other. The lower bell 12 has pivotally connected thereto a yoke 20 which in turn is pivotally connected to a tubular operating member 26.

A modified construction of the bell is disclosed in Figures 11 to 13 inclusive in which the upper bell 10' and the lower bell 12' are each provided with cut-out portions 14', each of which extends through an arc of approximately 45° , the pair of cut-out openings in each bell being oppositely related. With this construction, as in the previous construction of Figures 9 and 10, the distributing open-

ings may be closed entirely or varied, as desired.

Figures 1 to 4 inclusive show an installation with the improved large bell construction, such as disclosed in Figures 11 to 13, in association with a blast furnace and operating means for the valves. The top portion of a blast furnace 28 is shown, having at the top a chute 30 extending through a hood 32 closing the top of the hopper 14. 10' is the upper bell valve and 12' is the lower bell which is relatively rotatable to vary the size of the distributing openings. The small bell valve 34 controls the discharge from the chute 30 into the hopper 14 and is operative by a sleeve 36 in the usual manner through operating rods 38 to control the opening and closing of the valve 34. The rod 22 and the tube 26 extend through the sleeve 36. The rod 22 is threaded at its upper end to a bearing flange 38 which rests upon ball bearings 40 seating upon a housing flange 42 which is secured to the tube 26. The flange 38 has an upper cross shaped extension 44 provided with radial holes 46 which permit the insertion of auxiliary bars for the manual rotation of the flange 38 together with the rod 22 and the lower bell 12'.

In this construction the adjustment of the distributing openings by the relative rotation of the bell 12' with respect to the bell 10' is intended to be more or less permanent but may be manually modified, if found necessary. The flange 38, when in proper position, is secured to the flange 42 by bolts 48. The two bells are then secured for rotation as a unit. The flange 42 is secured by bolts 50 to an upper suspended flange 52. The space including the adjustable mechanism is enclosed by a cylindrical housing 54.

40 The supporting flange 52 rests upon ball bearings 56 which in turn rest upon the collar 58 of a raising and lowering shaft 60. The flange 52 is free to rotate with respect to the shaft 60 and has secured to its upper side, through flange 62, a wide-faced gear 64 which cooperates in meshing relation with a spur gear 66 during its vertical sliding movement. The spur gear 66 is carried by shaft 68, driven from shaft 70 through bevel gears 72-74. The shaft 70 is driven by motor 76 which is coupled to the shaft 70 through a speed reducer 78 and flexible coupling 80.

45 The rod 60 is provided with a squared portion 82 which cooperates with a suitable guide to prevent rotation of the rod 60. The rod 60 is connected at its upper end to a chain 84 which is attached to the large bell beam 86 which may be operated in any suitable manner.

50 The modified arrangement shown in Figures 5 to 8, inclusive, includes driving means for changing at will the relative size of the distributing opening by rotating the lower bell 12' with respect to the upper bell 10' and, in this arrangement, indicating means is dis-

closed for visibly indicating the size of the distributing opening at various times.

The driving mechanism comprises a motor 76, speed reducer 78, flexible coupling 80, driving shaft 70 and beveled gears 72-74, 70 substantially the same as in Figures 1 and 3. The vertical shaft 90 however which is driven from the gear 74 is a divided shaft, the lower part 90' being connected to the upper part 90 through a magnetic clutch 92. The upper part 90 of the shaft has a spur gear 94 secured thereto and the lower part 90' has a similar spur gear 96. The rod 22 is provided with a collar 98 which supports a flange 100 and above the flange 100 there is secured to the rod 22 a wide-faced gear 102 corresponding to the gear 64 in the previous construction.

As shown in the detail Figures 6 and 7, the gear 102 is split into two semi-circular sectors 104 and 106 in order to permit a ready replacement of the gear 102, if so desired. The rod 22 is supported by a bearing collar 108 at its upper end which rests upon ball bearings 110 and flange 112 which is secured to flange 114 and the raising and lowering rod 60 provided with a squared guide portion 82. The gear 102 is in meshing relation with the spur gear 94 throughout its vertical sliding movement. The tube 26 which is secured to the upper bell 10' is suspended from flange 116 which in turn is secured to flange 118 resting upon the flange 100 through ball bearings 120. The tube 26 is therefore free to have relative rotation with respect to the rod 22. A wide-faced split gear 122, constructed similar to gear 64, is secured to the tube 26 immediately below the flange 116 and is in meshing relation with the spur gear 96.

55 It will be understood that so long as the clutch 92 is engaged, the gears 94 and 96 will rotate together and therefore rotate the parts 10' and 12' of the large bell together. At any time however the operator, by releasing the clutch 92 thereby cutting out the drive to spur gear 96, may cause the lower bell 12' to rotate ahead of the bell valve 10' and thus vary the size of the distributing opening. This adjustment may be obtained without stopping the operation of the blast furnace.

We have disclosed in Figure 5 a diagrammatic system for visually indicating to the operator the relative size of the distributing opening of the large bell in the blast furnace. A pair of motors 124 and 126 are coupled respectively to the divided shaft parts 90 and 90' and are synchronized with a pair of motors 128 and 130 which may be placed at any desired point and connected through circuit connections 132. A source of A. C. current is shown at 134. The motors 124-126 are transmitters and the motors 128-130 are receivers and form a part of the indicating mechanism. The motors 128-130 are coupled through gearing 136 to drive a pair of 130

disks 138—140 which have cut-out portions corresponding to the cut-out portions in the bells 10' and 12' and which will rotate relative to each other whenever the bells 10' and 5 12' rotate with respect to each other. The operator is able to see at a glance the position of the bell members.

We claim:

1. In a blast furnace, a distributing large bell comprising a pair of conical members co-axially disposed, each of said conical members having a radial cut-out portion in its marginal edge which cooperate with each other to distribute material discharged into 15 the blast furnace, a tubular raising and lowering member secured to the upper conical member, a rod rotatable within said tube secured to the lower conical member, means for rotating said tubular member and rod as 20 a unit and means for interrupting the rotation of said rod while said tubular member continues to rotate to vary the effective size of the distributing opening.

2. In a blast furnace, a distributing large bell valve comprising a pair of co-axially positioned conical members, each of said conical members having a radial cut-out portion in its lower marginal edge which cooperate to provide a variable distributing opening 30 in the large bell, means for raising and lowering the large bell, means for rotating the conical members comprising the large bell and means for interrupting the rotation of one of said conical members while the other 35 of said conical members continues to rotate to vary the effective size of the distributing opening in the large bell.

3. In combination with a blast furnace, a distributing large bell having an adjustable distributing opening in its lower marginal edge, means for varying the effective size of the distributing opening without interrupting the operation of the blast furnace and means for visibly indicating the relative size 40 of the distributing opening in the large bell at a point remote from the blast furnace automatically during the operation thereof.

4. In combination with a blast furnace, a distributing large bell comprising a pair of cooperating conical members relatively rotatable to vary the distribution of material into said blast furnace, a rotatable shaft secured to each of said conical members extending vertically upward from the top of the 50 blast furnace, a drive shaft for rotating said shafts, a clutch in said drive shaft and means gearing said shafts to said drive shaft on opposite sides of said clutch whereby the relative rotative position of said conical members may be adjusted by control of said clutch.

5. In combination with a blast furnace, a distributing large bell in said blast furnace composed of a pair of relatively rotatable 65 conical members adjustable to vary the dis-

tribution of material in said blast furnace, a drive shaft, means for rotating one of said conical members directly from said drive shaft, means including a clutch coupling the other of said conical members for rotation to 70 said drive shaft and electrical indicating means for visibly indicating the relative position of said conical members at a point remote from the blast furnace.

6. In combination with a blast furnace, a distributing large bell valve in said blast furnace composed of a pair of relatively rotatable conical members adjustable to vary the distribution of material in said blast furnace, a drive shaft, means for rotating one of said conical members from said drive shaft, means for rotating the other of said conical members from said drive shaft in the same direction whereby said conical members normally rotate as a unit and clutch means for interrupting the rotation of one of said conical members to produce relative rotation therebetween and vary the distribution of material in the blast furnace.

7. In combination with a blast furnace, a distributing large bell valve in said blast furnace composed of a pair of conical members, each of which has a cut-out portion for controlling the distribution of material in said blast furnace, said conical members being normally rotatable as a unit but capable of relative rotation to vary the effective cooperation of the distributing openings, driving means for both of said conical members, clutch means for interrupting the rotation of one of said conical members to produce relative rotation therebetween, indicating means including a pair of disc members having cut-out portions proportionate to said conical members and means for rotating said disk members at speeds proportional to the rotation of said conical members whereby the effective distribution of material by said conical members in said blast furnace is 90 visibly indicated.

Signed at Chicago, Illinois, this 24th day of August, 1931.
